**HERBICIDAL COMPOSITION CONTAINING
 POLYCHLOROTOLUYL CHLORIDE**

Jack S. Newcomer, Wilson, Edward D. Weil, Lewiston, and Edwin Dorfman, Grand Island, N.Y., assignors to Hooker Chemical Corporation, Niagara Falls, N.Y., a corporation of New York
 No Drawing. Filed May 15, 1961, Ser. No. 109,881
 1 Claim. (Cl. 71—2.3)

This application is a continuation-in-part of Serial Number 714,965, filed in the United States Patent Office, February 13, 1958, now abandoned.

This application describes a novel class of chlorinated aromatic compounds useful as herbicides and chemical intermediates for the preparation of other herbicides and pesticides.

More particularly, this invention relates to herbicidal toluyl chlorides having at least one chlorine on the aromatic ring and at least one chlorine on the side chain, preferably having the structure:

wherein m is a positive integer from one to four and n is a positive integer from one to two.

The following acid chlorides are illustrative examples of the compounds of this invention:

$\alpha,2$ -dichloro-m-toluic,
 $\alpha,4$ -dichloro-m-toluic,
 $\alpha,5$ -dichloro-m-toluic,
 $\alpha,6$ -dichloro-m-toluic,
 $\alpha,2,4$ -trichloro-m-toluic,
 $\alpha,2,5$ -trichloro-m-toluic,
 $\alpha,2,6$ -trichloro-m-toluic,
 $\alpha,4,5$ -trichloro-m-toluic,
 $\alpha,4,6$ -trichloro-m-toluic,
 $\alpha,5,6$ -trichloro-m-toluic,
 $\alpha,2,4,5$ -tetrachloro-m-toluic,
 $\alpha,2,4,6$ -tetrachloro-m-toluic,
 $\alpha,2,5,6$ -tetrachloro-m-toluic,
 $\alpha,4,5,6$ -tetrachloro-m-toluic,
 $\alpha,\alpha,2$ -trichloro-m-toluic,
 $\alpha,\alpha,4$ -trichloro-m-toluic,
 $\alpha,\alpha,5$ -trichloro-m-toluic,
 $\alpha,\alpha,6$ -trichloro-m-toluic,
 $\alpha,\alpha,2,4$ -tetrachloro-m-toluic,
 $\alpha,\alpha,2,5$ -tetrachloro-m-toluic,
 $\alpha,\alpha,2,6$ -tetrachloro-m-toluic,
 $\alpha,\alpha,4,5$ -tetrachloro-m-toluic,
 $\alpha,\alpha,4,6$ -tetrachloro-m-toluic,
 $\alpha,\alpha,5,6$ -tetrachloro-m-toluic,
 $\alpha,\alpha,2,4,5$ -pentachloro-m-toluic,
 $\alpha,\alpha,2,4,6$ -pentachloro-m-toluic,
 $\alpha,\alpha,2,5,6$ -pentachloro-m-toluic,
 $\alpha,\alpha,4,5,6$ -pentachloro-m-toluic,
 $\alpha,\alpha,2,4,5,6$ -pentachloro-m-toluic,
 $\alpha,\alpha,\alpha,2$ -tetrachloro-m-toluic,
 $\alpha,\alpha,\alpha,4$ -tetrachloro-m-toluic,
 $\alpha,\alpha,\alpha,5$ -tetrachloro-m-toluic,
 $\alpha,\alpha,\alpha,6$ -tetrachloro-m-toluic,
 $\alpha,\alpha,\alpha,2,5$ -pentachloro-m-toluic,
 $\alpha,\alpha,\alpha,2,6$ -pentachloro-m-toluic,
 $\alpha,\alpha,\alpha,2,5,6$ -hexachloro-m-toluic and
 $\alpha,\alpha,\alpha,4,5,6$ -hexachloro-m-toluic,

3, α,α -trichloro-o-toluic,
 4, α,α -trichloro-o-toluic,
 5, α,α -trichloro-o-toluic,
 6, α,α -dichloro-o-toluic,
 5, 3, 4, α,α -tetrachloro-o-toluic,
 3, 5, α,α -tetrachloro-o-toluic,
 3, 6, α,α -tetrachloro-o-toluic,
 4, 5, α,α -tetrachloro-o-toluic,
 4, 6, α,α -tetrachloro-o-toluic,
 5, 6, α,α -tetrachloro-o-toluic,
 3, 4, 5, α,α -pentachloro-o-toluic,
 3, 4, 6, α,α -pentachloro-o-toluic,
 3, 5, 6, α,α -pentachloro-o-toluic,
 4, 5, 6, α,α -pentachloro-o-toluic,
 3, 4, 5, 6, α,α -hexachloro-o-toluic,
 3, α,α,α -tetrachloro-o-toluic,
 4, α,α,α -tetrachloro-o-toluic,
 5, α,α,α -tetrachloro-o-toluic,
 6, α,α,α -tetrachloro-o-toluic,
 3, 4, α,α,α -pentachloro-o-toluic,
 3, 5, α,α,α -pentachloro-o-toluic,
 3, 6, α,α,α -pentachloro-o-toluic,
 4, 5, α,α,α -pentachloro-o-toluic,
 4, 6, α,α,α -pentachloro-o-toluic,
 5, 6, α,α,α -pentachloro-o-toluic,
 3, 4, 5, 6, α,α,α -hexachloro-o-toluic,
 3, $\alpha,\alpha,\alpha,\alpha$ -tetrachloro-o-toluic,
 4, $\alpha,\alpha,\alpha,\alpha$ -tetrachloro-o-toluic,
 5, $\alpha,\alpha,\alpha,\alpha$ -pentachloro-o-toluic,
 6, $\alpha,\alpha,\alpha,\alpha$ -pentachloro-o-toluic,
 3, 4, 5, 6, $\alpha,\alpha,\alpha,\alpha$ -heptachloro-o-toluic,
 2, α -dichloro-p-toluic,
 3, α -dichloro-p-toluic,
 2, 3, α -trichloro-p-toluic,
 2, 5, α -trichloro-p-toluic,
 2, 6, α -trichloro-p-toluic,
 3, 5, α -trichloro-p-toluic,
 2, 3, 5, α -tetrachloro-p-toluic,
 2, 3, 6, α -tetrachloro-p-toluic,
 2, 3, 5, 6, α -pentachloro-p-toluic,
 2, α,α -trichloro-p-toluic,
 3, α,α -trichloro-p-toluic,
 2, 3, 5, α,α -tetrachloro-p-toluic,
 2, 3, 5, 6, α,α -pentachloro-p-toluic,
 2, 3, 5, 6, α,α -hexachloro-p-toluic,
 2, α,α,α -tetrachloro-p-toluic,
 3, α,α,α -trichloro-p-toluic,
 2, 3, α,α,α -pentachloro-p-toluic,
 2, 3, 5, α,α,α -hexachloro-p-toluic,
 2, 3, 6, α,α,α -hexachloro-p-toluic,
 2, 3, 5, α,α,α -heptachloro-p-toluic acid chlorides.

Although all of the above compounds are herbicidal the preferred embodiment of the compositions of this invention because of ease of preparation, availability and the like are those compositions having a total of from four to seven chlorine atoms.

While there is no paucity of herbicides per se, there is a real need for low-volatility, low drift herbicides which possess a greater margin of safety in respect to desirable plant species. For example, herbicides such as 2,4-D and 2,4,5-T frequently damage crops on the peripheral portions of treated areas because of spray drift and volatility. This tendency is so well recognized that the use of 2,4-D and its derivatives are prohibited or restricted in many crop areas. The reason for the damage is the extreme phytotoxicity of 2,4-D herbicidal products, particularly against broadleaf plants, coupled with the tend-

ency to drift. Thus, even though the rates of the herbicides applied is less than a killing application, there is sufficient concentration of herbicide to cause undesirable hormonal effects such as twisting, leaf area repression and wilting.

The compositions of this invention in contrast have good phytotoxicity toward broadleaf and grassy plants yet are much safer to use.

Another important and desirable attribute that the compositions of this invention possess over the prior art is the rapid dissipation of their phytotoxicity in the soil. This means that shortly after the herbicide has been applied and exerted its phytotoxic effect against the weed species treated, the compounds break down in some manner so that no toxic residue persists in the soil to damage follow-up and subsequent crops. This offers the obvious economic advantage of allowing full use of high value farmland rather than allowing to remain fallow. No reason or mechanism is advanced why this rather ephemeral phytotoxicity is found in these compounds, when toxic residues of many related structures persist in the soil for periods of time ranging from several months to a year or more in extreme cases. Thus, many commercial herbicides such as herbicidal chlorates, the chlorinated benzoic acids, and the related ring chlorinated toluiic acids leave long term toxic residues in the soil making the planting of sequential crops risky or impossible.

In addition to their herbicidal utility, the compounds of the invention not only have utility as herbicides but also are valuable as chemical intermediates. By reaction with ammonia, N-alkyl amines, N,N-dialkylamines, and anilines, they yield new amides and anilides having biocidal insect repellent herbicidal utility. The amides bearing one or two chlorines on the α -position can be further reacted with O,O-dimethyl phosphorodithiolate salts and O,O-diethyl phosphorodithiolate salts to produce useful insecticides and miticides of the structure:

where m is as above, and where R^1 and R^2 are hydrogen, alkyl or aryl, and y is one or two.

An additional advantage of the novel method of this invention is that it lends itself to the use of the toxicant in various grades of purity ranging from the highly purified oil or crystalline product to a technical crude. Furthermore, these herbicidal compositions offer the advantage of compatibility with a host of other herbicides including the tri- and tetrachlorophenylacetic acids and 2,4-D and other herbicidal phenoxy aliphatic acids and esters, simazine and other herbicidal triazines, monuron, fenuron, diuron, and other herbicidal ureas, petroleum oils, hexachlorocyclopentadiene, pentachlorophenol, dinitro-o-alkylphenols, glycol, trichloroacetates, 2,2-dichloropropionates, with insecticides such as benzene hexachloride and chlordane, and with various adjuvants and diluents well known to the art. Thus, these herbicides may be used by themselves or made the subject of liquid or solid formulations ranging from the very simple to the most complex. For example, if it is desired these compositions may be made the subject of a liquid formulation by diluting, dispersing, dissolving or emulsifying with a surface active adjuvant or combination of these adjuvants in solvents such as petroleum hydrocarbons, ketones, esters or combinations thereof. Or alternatively, the novel herbicides may be made up as solid formulations of powders, dusts, wettable powders, granules and pellets using solid diluents such as talcs, clays, flours, starches, diatomaceous earths, mica, alkaline earth limes, carbonates and phosphates either finely divided, granular or pelleted in form. Unlike aliphatic and some aromatic acid chlorides, the

compounds of the invention are relatively stable to water and consequently formulations of these compounds can be dispersed in water for spraying without fear of decomposition.

5 These solid and liquid formulations facilitate handling and application and sometimes enhance herbicidal activity to more than an additive degree.

Solutions of the compounds of the invention in mineral oils, kerosene, diesel oils, weed oils, and the like are particularly effective, giving rapid and thorough kill of mixed 10 weed populations at rates and costs much lower than would be required in using either component alone. A major advantage of the compounds of the invention over related acids and amides is their high solubility in oils, which permits their use as herbicidal oil fortifiers.

The liquid compositions, whether solutions or dispersions of the active agents in a liquid solvent and also the wettable powder or dust compositions of this invention may contain as a conditioning agent one or more surface

20 active agents in amounts sufficient to render the composition readily dispersable in water. By the term surface active agents are included wetting agents, dispersing agents, emulsifying agents and the like. A satisfactory but not complete list of such agents is set forth in an

25 article in "Soap and Chemical Specialties," vol. 31, No. 7, pages 50-61; No. 8; pages 48-61; No. 9, pages 52-67, and No. 10, pages 38 (67), 1955. Other sources of adjuvant materials is set forth in Bulletin E-607 of the Bureau of Entomology and Plant Quarantine of the United States

30 Department of Agriculture. Polyoxyethyl esters and ethers are particularly efficacious emulsifiers for these compositions.

While the manner and method of application of the inventive compositions is varied and largely dependent 35 upon the climatic conditions, crop treated, the weeds to be eradicated, the equipment available and the convenience of the user, a preferred embodiment of this invention is to apply these herbicides as a spray after making them

40 up as a liquid formulation comprised of several times their weight of petroleum hydrocarbon solvents and oils such as xylene with small quantities of an emulsifier such as a commercial polyoxyethylene ether and a surfactant such as alkylaryl sulfonate mixture. This type of mixture is emulsified with water and sprayed on the weed popula-

45 tion growing amidst the desired crop or other area where weed growth is not desired. Or alternatively, these compositions may be applied as a solid formulation directly to the ground.

The rate of application cannot be precisely stated due

50 to varying degree of resistance possessed by the weed species and crop, the stage of weed and crop growth, the soil type and climatic conditions, but in general, the rates will be at least one-quarter of a pound of herbicide per acre and for reasons of cost will seldom exceed one

55 hundred pounds per acre with the preferred range falling within one-half to fifty pounds per acre. Where the weeds are in an early stage of growth, they being more susceptible, will frequently respond to the rates from one-half to four pounds per acre while older weeds or weeds

60 that are to be totally eradicated from ornamental beds or turf may require rates in excess of four pounds per acre. In those instances where the weed population has been allowed to accumulate unchecked or where mature plants are encountered, applications of up to fifty and

65 even beyond this rate may be required. For eradication of deeply-rooted herbicide-resistant perennial weeds such as field bindweed, rates of ten to one hundred pounds are found best. In oil sprays, concentrations of 0.1 to ten percent of the toxicant in the oil are preferred, the oil 70 being sprayed at the rate of ten to two hundred gallons per acre.

The compounds of the invention may be synthesized by a number of routes, including the following:

A. Side chain chlorination of ring-chlorinated toluiyl 75 chlorides or toluiic acids.

This reaction is ordinarily accomplished by passing Cl_2 gas, liquid Cl_2 , or sulfuryl chloride into the liquid compound to be chlorinated or a solution thereof in an inert chlorination solvent such as carbon tetrachloride, employing light as catalyst or employing catalytic amounts of a peroxide such as benzoyl peroxide as catalyst. Suitable temperatures are from minus seventy degrees (convenient where liquid chlorine is employed), to plus two hundred and twenty degrees. At higher temperatures, chlorinolysis of the $-\text{COX}$ group and/or the $-\text{CH}_3-\text{nCl}_n$ group may be a troublesome side reaction. Where the acid is thus produced, it is converted to the chloride by heating with at least one mole of thionyl chloride, PCl_5 , or benzotrichloride.

B. Ring chlorination of side chain chlorinated toluyl chlorides or toluic acids.

This reaction is accomplished generally by passing Cl_2 gas or SO_2Cl_2 into the liquid reactant or solution of the reactant in an inert chlorination solvent such as carbon tetrachloride employing a Lewis acid as a catalyst, for example, a few percent or less of FeCl_3 , SbCl_5 , SnCl_4 , TiCl_4 , ICl_3 , MoCl_5 , BF_3 , AlCl_3 , or $\text{AlCl}_3\text{S}_2\text{Cl}_2$. Temperatures of from zero degrees centigrade to one hundred and fifty degrees are preferred, higher temperatures may cause side chain chlorination or chlorinolysis, lower temperatures cause sluggish reaction. The acid chloride ($\text{X}=\text{Cl}$) is preferred in these reactions. Where the acid is employed, HOCl or NaOCl may be used as ring-chlorination reagent in aqueous solution at zero degrees to one hundred degrees centigrade and pH two to seven. Where the acid is thus produced it is converted to the chloride by refluxing with an excess of thionyl chloride.

C. Chlorination of xylenes on the ring and on the side chain, until at least one side chain bears three chlorine atoms, then hydrolysis of the trichloromethyl group by at least one molar equivalent of water to produce a $-\text{COCl}$ group.

This reaction is conveniently accomplished by passing Cl_2 into xylene under the conditions for ring chlorination (Lewis acid catalyst), removing the catalyst (by distillation or washing with water), when the desired level of ring chlorination has been reached, then passing Cl_2 under photochemical or free radical catalysis until the desired level of side chain chlorination has been reached, and until the molecule has at least one $-\text{CCl}_3$ group. The other CH_3-nCl_n group will generally then be a $-\text{CHCl}_2$ or a $-\text{CCl}_2$ group.

Reacting one mole of water with this intermediate at about fifty to two hundred and fifty degrees centigrade in the presence of an acid catalyst such as H_2SO_4 , ZnCl_2 , or FeCl_3 will yield the $-\text{COCl}$ group, by hydrolysis of the $-\text{CCl}_3$.

A variation of this route, to prepare those compounds of the invention where $n=1$, is to chlorinate the ring-chlorinated xylenes under side-chain chlorination conditions as above described, until one methyl group bears one chlorine atom and the other methyl group bears two chlorine atoms, then to hydrolyze under acid catalyzed conditions as above described, which leaves the $-\text{CH}_2\text{Cl}$ group intact and converts the $-\text{CHCl}_2$ group to $-\text{CHO}$. The $-\text{CHO}$ group then reacts preferentially with chlorine under photochemical catalysis to form the $-\text{COCl}$ group.

The following examples are intended to illustrate the workings of this invention including such facets as the preparation of the herbicidal compositions, their formulation as herbicidal agents, and the testing results obtained using them.

Example 1.—Preparation of mixed isomers of ring-dichlorinated side chain mono- and dichlorinated o-tolyl chloride

Five parts of o-toluic acid and ten parts of acetic acid were dissolved in two hundred parts of five percent aqueous sodium hypochlorite and allowed to stand at room temperature for 3.5 hours, then acidified with hydrochloric acid to pH two and filtered. Seven parts of white solid was obtained, having a neutralization equivalent of two hundred and two (theory for dichloro-o-toluic acid, two hundred and five). Treatment of a small sample of this product with refluxing 0.1-N KOH in methanol caused no release of chloride ion, proving the chlorine atoms to be on the ring. Infrared evidence showed the mixture to contain substantial 3,6-and 4,5-dichloro-o-toluic acid, by comparison with authentic samples.

Dichloro-o-tolyl chloride was prepared from this mixed dichloro-o-toluic acid by refluxing for one day with five parts of thionyl chloride followed by distillation to obtain the fraction boiling at one hundred and twenty to one hundred and forty-two degrees centigrade (eight mm.), which had the correct analysis for dichloro-o-tolyl chloride.

This intermediate was treated with chlorine gas at ninety to one hundred and five degrees under illumination by a four hundred watt mercury vapor lamp until one molar equivalent of hydrogen chloride was evolved. The product was a colorless liquid, having the proper analysis for a trichlorotolyl chloride having one chlorine atom on the methyl side chain.

Analysis.—Calcd. for $\text{C}_8\text{H}_4\text{Cl}_4\text{O}$: Cl (total), 55.1 percent; Cl (hydrolyzable by KOH), 27.5 percent. Found: Cl (total), 54.1 percent; Cl (hydrolyzable by KOH), 27.4 percent.

Continuance of the chlorination until a total of two molar equivalents of hydrogen chloride were evolved gave a viscous colorless liquid having an analysis approximating to that for tetrachloro-o-tolyl chloride having two chlorine atoms on the side chain.

Analysis.—Calcd. for $\text{C}_8\text{H}_3\text{Cl}_5\text{O}$: Cl (total), 60.8 percent; Cl (hydrolyzable), 36.4 percent. Found: Cl (total), 58.0 percent; Cl (hydrolyzable), 33.6 percent.

Example 2

Mixed dichloro-m-xylene was made by passing Cl_2 into three hundred and eighteen parts of m-xylene containing 0.3 percent ferric chloride at thirty-seven to forty-two degrees centigrade until one hundred and eighty-two parts of hydrogen chloride evolved. The crude product was then fractionated at ten mm., and the fraction boiling at ninety to one hundred and ten degrees centigrade taken as dichloro-m-xylene. Chromatographic analysis shows this to be a mixture of 4,5-, 4,6-, 2,4-, 2,5- and 5,6-isomers.

Chlorine gas was passed into 88.5 parts of this dichloro-m-xylene at one hundred to one hundred and seventy degrees under irradiation by a four hundred watt mercury vapor lamp until ninety parts of hydrogen chloride were

given off. The viscous syrup which remained had the correct chlorine analysis for $P, Q, \alpha, \alpha, \alpha, \alpha', \alpha'$ -heptachloro-m-xylene (P and Q indicate ring positions).

Approximately five percent by weight of concentrated sulfuric acid was added to this intermediate, then water was added dropwise at one hundred and twenty degrees with stirring, until one molar equivalent of hydrogen chloride was evolved. This required about one molar equivalent of water. The crude product was fractionated to obtain P, Q, α, α -tetrachloro-m-tolyl chloride, boiling at one hundred and sixty to one hundred and seventy-five degrees (2.5 mm.).

Example 3.—Preparation of $\alpha, 2, 3, 5, 6$ -pentachloro-p-tolyl chloride and $\alpha, \alpha, 2, 3, 5, 6$ -hexachloro-p-tolyl chloride

A solution consisting of 154.5 parts of p-tolyl chloride, two parts of iodine and two parts of $FeCl_3$ is heated to ninety degrees centigrade. At this temperature chlorine gas is introduced. The reaction temperature is raised during the chlorination to one hundred and fifty degrees centigrade. The chlorination continues until one hundred and forty-six parts of gaseous hydrogen chloride evolves. The resulting material is fractionated removing the desired product which boils at one hundred and twenty-two to one hundred and twenty-eight degrees centigrade at 0.25 mm. and sets to a solid on standing.

Analysis.—Calcd. for $C_8H_3OCl_5$: Cl, 60.0 percent. Found: Cl, 59.1 percent.

One hundred and forty-six parts of 2,3,5,6-tetrachloro-p-tolyl chloride is heated to one hundred and forty to one hundred and sixty degrees centigrade, exposed to an ultraviolet light as the chlorination catalyst, and gaseous chlorine is introduced until 18.3 parts of hydrogen chloride is evolved. A viscous liquid product is obtained, which on storage sets to a waxy semi-solid.

Analysis.—Calcd. for $C_8H_2OCl_6$: Cl, 65.0 percent. Found: Cl, 65.0 percent.

Eighty-two parts of the compound obtained from step 2 is heated to one hundred and forty to one hundred and sixty degrees centigrade, using an ultraviolet light as the chlorination catalyst. Gaseous chlorine is introduced until 9.2 parts of hydrogen chloride evolves. A colorless viscous oil is obtained, which, on storage sets to a wax.

Analysis.—Calcd. for C_8HOCl_7 : Cl, 69.0 percent. Found: Cl, 68.6 percent.

Example 4.— $\alpha, \alpha, \alpha, 4$ -tetrachloro-m-tolyl chloride and $\alpha, \alpha, \alpha, 4$ -tetrachloro-m-toluic acid

One hundred parts by weight of 4-chloro-m-xylene is heated to one hundred and fifty to one hundred and seventy degrees and exposed to a mercury vapor lamp while introducing chlorine gas. When no further hydro-

gen chloride gas is evolved and no further weight uptake occurred, the product is assumed to be the desired, $\alpha, \alpha, \alpha, \alpha', \alpha', \alpha'$ -4-heptachloro-m-xylene. To this intermediate is added five percent by weight of concentrated sulfuric acid and the mixture stirred at one hundred and twenty-five to one hundred and forty degrees, while a one molar equivalent of water is added dropwise over two hours, causing the evolution of two molar equivalents of hydrogen chloride. The crude product is washed with ice water to remove the sulfuric acid and then fractionally distilled at reduced pressure.

The fraction boiling at one hundred and thirty to one hundred and forty degrees (0.01 mm.), is taken as the desired $\alpha, \alpha, \alpha, 4$ -tetrachloro-m-tolyl chloride, a waxy colorless semi-solid at room temperature.

Analysis.—Calcd. for $C_8H_3OCl_5$: Cl, 60.7 percent. Found: Cl, 59.5 percent.

Example 5.—Preparation of $\alpha, \alpha, \alpha, 2, 5$ -pentachloro-p-tolyl chloride

Chlorine gas was passed into 2,5-dichloro-p-xylene at one hundred and fifty to one hundred and ninety degrees under illumination by an ultraviolet lamp until no further hydrogen chloride evolution occurred. The product, recrystallized from benzene-ligroin mixture, melted at one hundred and eighty degrees and had the correct chlorine and hydrolyzable chlorine analysis for the expected $\alpha, \alpha, \alpha, \alpha', \alpha', 2, 5$ -octachloro-p-xylene. This product melted at 198.5 to 199.5 degrees centigrade.

A mixture of one hundred and ninety parts of this octachloro-p-xylene, one hundred and ninety parts of trichlorobenzene as solvent, and ten parts of concentrated sulfuric acid was heated to one hundred and twenty to one hundred and thirty degrees and stirred, whereupon nine parts of water was added dropwise over several hours, causing evolution of thirty-six parts of hydrogen chloride. The product was then washed with water and fractionally distilled, the fraction boiling at one hundred and sixty-five to one hundred and eighty-two degrees (seven mm.), being collected as the desired $\alpha, \alpha, \alpha, 2, 5$ -pentachloro-p-tolyl chloride. This colorless material, which was not further purified, solidified to a waxy solid and was shown to be the desired acid chloride by the fact that upon heating with several parts by weight of sodium carbonate in methanol, one molar equivalent of chloride ion was released with formation of methyl $\alpha, \alpha, \alpha, 2, 5$ -pentachloro-p-toluate.

Example 6

The preparations of further members of the class of compounds of the invention is given tabularly as follows:

Compound	Starting Materials	Method	Reaction Conditions	Boiling Point
$\alpha, 4$ -dichloro-m-tolyl chloride	4-chloro-m-toluic acid	A	Reflux with 10 pts. $SOCl_2$ 12 hrs., strip, pass in Cl_2 gas at 150° under irradiation by UV lamp until theoretical weight increase.	95-105° (1 mm.).
α, P -dichloro-m-tolyl chloride	m-Tolyl chloride	A	Add 1% $FeCl_3$ pass in Cl_2 at 30° until one molar equiv. HCl evolved, then distill off the X -chloro-m-tolyl chloride and chlorinate the distillate as above. Distill product.	95-105° (1 mm.).
$\alpha, 4, 6$ -trichloro-m-tolyl chloride	4,6-dichloro-m-toluic acid	A	As in first case above.	110-115° (1 mm.).
$\alpha, 4, 5, 6$ -tetrachloro-m-tolyl chloride	4,5,6-trichloro-m-toluic acid	A	As above.	130-140° (1 mm.).
$\alpha, \alpha, 4$ -trichloro-m-tolyl chloride	4-chloro-m-xylene	C	Pass in chlorine at $150-170^\circ$ until theoretical wt. increase for pentachlorination using ultraviolet radiation. Then add 5% conc. H_2SO_4 by weight, then one molar equiv. water dropwise at $120-150^\circ$ C. Distill product.	110-115° C. (1 mm.).
$\alpha, \alpha, 4, 6$ -tetrachloro-m-tolyl chloride	4,6-dichloro-m-xylene	C	As above.	130-140° (1 mm.).
$\alpha, \alpha, 4, 5, 6$ -pentachloro-m-tolyl chloride	4,5,6-trichloro-m-xylene	C	As above.	150-165° (1 mm.).
$\alpha, \alpha, 4, 5, 6$ -hexachloro-m-tolyl chloride	do	C	As above.	157-167° (1 mm.).
$\alpha, \alpha, 4, 6$ -pentachloro-m-tolyl chloride	4,6-dichloro-m-xylene	C	As above, but chlorinated to theoretical weight increase for hexachlorination.	150-155° (1 mm.).
$\alpha, 5$ -dichloro-o-tolyl chloride	5-chloro-o-toluic acid	A	Reflux with 5 pts. $SOCl_2$ 12 hrs., strip, pass in Cl_2 at 150° under UV light until theoretical weight increase.	98-108° (1 mm.).

Compound	Starting Materials	Method	Reaction Conditions	Boiling Point
$\alpha,\alpha,5$ -trichloro-o-tolyl chloride	5-chloro-o-toluic acid	A	As above	110-115° (1 mm.).
$\alpha,\alpha,5$ -tetrachloro-o-tolyl chloride	do	A	As above	130-140° (1 mm.).
$\alpha,\alpha,4,5$ -tetrachloro-o-tolyl chloride	4,5-dichloro-o-xylene	C	Pass in Cl_2 at 150-170° under UV light until theoretical weight increase for pentachlorination. Add 5% conc. H_2SO_4 , then one molar equiv. water dropwise at 120-150°.	130-140° (1 mm.).
$\alpha,\alpha,3,6$ -tetrachloro-o-tolyl chloride	3,6-dichloro-o-xylene	C	As above	128-138° (1 mm.).
$\alpha,\alpha,4,5,6$ -hexachloro-m-tolyl chloride	4,5,6-trichloro-m-xylene	C	As above	150-160° (1 mm.).
$\alpha,\alpha,3,4,5,6$ -hexachloro-o-tolyl chloride	Tetrachloro-o-xylene	C	Pass in chlorine at 150-170° under UV until theoretical wt. increase for pentachlorination. Add 5% conc. H_2SO_4 , then one molar equiv. water dropwise at 120-150°.	160-167° (1 mm.).
$\alpha,\alpha,3$ -trichloro-p-tolyl chloride	3-chloro-p-xylene	C	As above	110-115° (1 mm.).
$\alpha,3$ -dichloro-p-tolyl chloride	3-chloro-p-toluic acid	A	As prep. A above	105-110° (1 mm.).
$\alpha,\alpha,2,5$ -tetrachloro-p-tolyl chloride	2,5-dichloro-p-xylene	C	As prep. C above	135-140° (1 mm.).
$\alpha,\alpha,\alpha,2,5$ -pentachloro-p-tolyl chloride	do	C	As prep. C above except chlorination carried to hexachlorination level.	150-155° (1 mm.).
$\alpha,\alpha,2,3,5$ -pentachloro-p-tolyl chloride	2,3,5-trichloro-p-xylene	C	As prep. C above	150-155° (1 mm.).
$\alpha,2,5$ -trichloro-p-tolyl chloride	2,5-dichloro-p-toluic acid	A	As prep. A above	110-115° (1 mm.).
$\alpha,3,4,5,6$ -pentachloro-o-tolyl chloride	Tetrachloro-o-toluic acid	A	Reflux with 10 pts. $SOCl_2$ 12 hrs., strip, pass in Cl_2 at 150° under UV light until theoretical wt. increase.	145-155° (1 mm.).

Example 7.—Preparation of emulsifiable concentrate formulation

Pounds 25
 $\alpha,2,5$ -trichloro-p-tolyl chloride 2
 Polyoxyethylene laurate emulsifier 0.5
 Xylene to make total one gallon.

This produced a solution emulsifiable with water to prepare a sprayable emulsion.

Example 8.—Preparation of oil solution formulation

The following were blended:

Pounds 35
 $\alpha,\alpha,3,6$ -tetrachloro-o-tolyl chloride 5
 Diesel oil 95

This produced a clear solution sprayable as such.

Example 9.—Formulation of granular formulation

Granular clay, twenty-four to forty-eight mesh, was tumbled at one hundred degrees centigrade and sprayed with molten $\alpha,5$ -dichloro-o-tolyl chloride until a formulation containing ten percent by weight of the latter was obtained. This formulation was free-flowing and could be spread by hand or from a fertilizer spreader on the areas to be treated.

Example 10

An area of weedy farmland infested with ragweed, 50 pigweed, lambsquarters, crabgrass, foxtail and mustard is sprayed with the chemicals of Examples 2, 3, 4 and 5 in a formulation as described in Example 8, at the rate of twenty pounds of the acid chloride per acre. Substantially one hundred percent destruction of the above-ground portions of the above weeds is obtained within one week of spraying.

One month later, the area is plowed, disked, and planted to soybeans, which germinate and grow normally.

On the other hand, after spraying of test plots in the same field with twenty pounds of 2,3,6-trichlorobenzoic acid or 3,6-dichloro-o-toluic acid (giving equal weed destruction), severe stunting and malformation of soybeans is observed and even the following year, some malformation is observed when soybeans are planted in the treated 65 area.

Example 11.—Herbicidal use of $\alpha,\alpha,2,3,5,6$ -pentachloro-p-tolyl chloride

A field area infested with seeds of wild oats and broadleaf annual weeds, principally ragweed, lambsquarters, and pigweed was plowed, disked, and seeded with corn. Prior to corn and weed germination, the area was sprayed at the rate of eight pounds (of active ingredient), per acre with an emulsifiable formulation of $\alpha,\alpha,2,3,5,6$ -penta-

chloro-p-tolyl chloride dispersed in water. One month later, the area was found to bear a healthy stand of corn, essentially weed free. Comparison plots either left unsprayed or sprayed at the rate of eight pounds per acre with 2,3,5,6-tetrachloro-p-tolyl chloride were infested with broadleaf weeds and wild oats.

Example 12

Five percent solutions of the compounds of Examples 1-6 in kerosene were prepared. These solutions were sprayed at the rate of fifty gallons per acre on mixed weed populations composed mainly of dock, chicory, wild carrot, dandelion, goldenrod, and oxeye daisy. After two days, substantially complete destruction of the foliage of these weeds was noted. The use of the kerosene alone, without fortifier, gave only about twenty percent foliar destruction of goldenrod and dandelion and negligible damage to the other weed species.

We claim:

A herbicidal composition comprising a minor proportion of a herbicidal compound of the chemical formula

where m is from one to four and n is from one to two, 55 a minor proportion of another herbicidal material, a minor proportion of a surface active agent and a major proportion of a liquid diluent material which facilitates application of the herbicides to loci where herbaceous growth is to be inhibited.
